United States Patent Office.

HERMANN ILENBURG, OF PHILADELPHIA, PENNSYLVANIA, ASSIGNOR TO MACKELLAR, SMITHS & JORDAN, OF SAME PLACE.

Design No. 3,813, dated January 11, 1870.

DESIGN FOR PRINTERS' TYPE.

The Schedule referred to in these Letters Patent and making part of the same.

To all whom it may concern :

Be it known that I, HERMANN ILENBURG, (assignor to MacKellar, Smiths & Jordan,) of the city and county of Philadelphia, Pennsylvania, have invented and produced a new and original Design for Printing-Type, of which the following is a specification.

The nature of my design is fully shown in the accompanying impressions, in which the capital and small letters are shown, and the design shown is preserved in any figures, signs, or symbols that may be required.

In the word "bank," a modification of the design is shown, the body of the letter being left open, or partially filled up.

Claim.

I claim, as my invention, the design for printing-type, as shown.

HERMANN ILENBURG.
